PENCIL CLIP

Eric S. Powell, Evansville, Ind.

Application August 2, 1938, Serial No. 222,723

1 Claim. (Cl. 120—84)

The invention relates to a pencil clip and more particularly to a combined pencil clip and lead sharpener.

The primary object of the invention is the provision of a device of this character, wherein the same when carried upon a pencil will enable the latter to be held in a pocket of a garment and thus avoiding the loss of the pencil by the dropping of the same accidentally from the pocket and additionally the device will sharpen the tip of the lead of the pencil, being usable for this purpose.

Another object of the invention is the provision of a device of this character, wherein the construction of the same is novel in its entirety and is provided with a guide way for the sharpened end of the pencil so that the lead at the exposed tip thereof can be conveniently pointed or sharpened for the pointing of the same.

A further object of the invention is the provision of a device of this character, wherein the same is in a single unit being cut and stamped or otherwise formed from a single blank of metal and when upon the pencil will enable it to be clipped in carrying position upon the person and also serviceable as a sharpener for the lead of the pencil.

A still further object of the invention is the provision of a device of this character, which is simple in its construction, thoroughly reliable and efficient in operation, being for a dual purpose, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

40 In the accompanying drawing:

Figure 1 is a fragmentary side elevation of a pencil showing the clip constructed in accordance with the invention in applied position for the sharpening of the lead of the pencil.

45 Figure 2 is a sectional view of the clip taken on the line 2—2 of Figure 1 looking in the direction of the arrows.

Figure 3 is a sectional view of the clip taken on the line 3—3 of Figure 1 looking in the direction of the arrows.

50 Figure 4 is a plan view of the clip removed from the pencil.

Figure 5 is a fragmentary vertical longitudinal sectional view through the clip when in position for sharpening the lead of the pencil.

Figure 6 is a sectional view taken on the line 6—6 of Figure 5, the pencil being removed.

Similar reference characters indicate corresponding parts throughout the several views in the drawing.

Referring to the drawing in detail, A designates generally a portion of a pencil, B the pointed lead tip thereof and C the tapered portion of the body of the pencil or its stock adjacent to said tip B, respectively, while D denotes generally the clip constituting the present invention and hereinafter fully described.

The clip D comprises a longitudinally slotted skeleton sleeve-like member 10 which is inherently resilient and is susceptible of embracing the stock of the pencil A for frictional security thereon. Integrally formed with this member 10 diametrically opposite to the slit area 11 therein is an outwardly arched clamping jaw 12 being struck outwardly longitudinally thereof to provide a guide way or channel 13 for the tip B of the pencil A when the member 10 is telescoped over the tapered portion C of the stock of said pencil for a purpose presently described.

The jaw 12 has an outwardly, downwardly, 25 upwardly and inwardly curled strip-like terminal 14 which is provided with a notch 15 opening through its free end edge, the opposite side walls of the said notch presenting cutting edges 16 while the free end edge of the terminal 14 approaches closely to the way or channel 13 so that the knife edged notch 15 will confront the tip B of the pencil A when the latter is inserted through the member 10 and such tip B traverses the channel or way 13 in the direction of the terminal 14 and the said tip is introduced into the notch 15. Now when the pencil A is rotated in the member 10 with said pencil in the position as just referred to, the edges 16 of the notch 15 will sharpen the tip B for the pointing.

The terminal 14 on the jaw 12 effects a gripping knob when the clip is worn on the stock of the pencil A whereby the latter can be clamped in a carrying position within a garment and thus the loss accidentally of the pencil is avoided.

The jaw 12 is transversely arched or bowed and in this way the channel or way 13 is formed therein for effecting a guide for the tip end of the pencil A when the clip is utilized as a sharpener for the pointing of the lead of said pencil.

The cutting edges at the notch 15 are at the outermost area of the way or channel 13, and in fact, this notch 15 is in the terminal 14 as will be apparent in Figures 5 and 6 of the drawing. The free ends of the terminal follow an angular

relationship to the jaw of the clip so that these areas approach each other and thus the lead tip B will be acted upon by the cutting edges for the sharpening and pointing of said tip.

5. What is claimed is:

A clip of the kind described comprising a longitudinally slotted sleeve-like member inherently resilient and susceptible of embracing a pencil stock, an outwardly arcuately curved jaw formed 10 with said member and extended beyond one end

thereof and having a guideway longitudinally provided therein, and an outwardly, downwardly and inwardly curled terminal formed with said jaw and having a notch opening through its free edge to provide cutting areas opposite each other closely approaching the guideway in said jaw, the said cutting areas being disposed at opposite sides of the guideway in the jaw and in proximity to the jaw next to the said terminal.
